United States Patent Office

Des. 188,928
Patented Sept. 27, 1960

188,928

ASH TRAY

Anthony B. Laganella, 1824 Dudley, and Charles E. McMenamin, 554 Acorn St., both of Philadelphia, Pa.

Filed Nov. 5, 1959, Ser. No. 58,216

Term of patent 14 years

(Cl. D85—2)

FIG. 1

FIG. 2

FIG. 3

FIG. 4

FIG. 5

Fig. 1 is a front elevational view of an ash tray, showing our new design;

Fig. 2 is a side elevational view looking from the right of Fig. 1;

Fig. 3 is a top plan view;

Fig. 4 is a bottom plan view; and

Fig. 5 is a perspective view thereof.

We claim:

The ornamental design for an ash tray, as shown.
